UNITED STATES PATENT OFFICE.

KENNETH HOWIE, OF NORRISTOWN, AND WILLIAM O. TAYLOR, OF LIMERICK, PENNSYLVANIA, ASSIGNORS TO WILDMAN MFG. CO., OF NORRISTOWN, PENNSYLVANIA, A CORPORATION OF PENNSYLVANIA.

STRIPING MECHANISM FOR KNITTING MACHINES.

Application filed September 9, 1920, Serial No. 409,265. Renewed November 29, 1924.

To all whom it may concern:

Be it known that KENNETH HOWIE and WILLIAM O. TAYLOR, citizens of the United States, and residents of Norristown, Pennsylvania, and Limerick, Pennsylvania, respectively, have invented certain new and useful Improvements in Striping Mechanism for Knitting Machines, of which the following is a specification.

10 The invention concerns striping mechanism for knitting machines, and it consists in the features and combination and arrangement of parts hereinafter described and particularly pointed out in the appended claims.

In the accompanying drawings—

Fig. 1 is a plan view of a portion of the head of a circular knitting machine, embodying the invention.

20 Fig. 1^a shows cam parts.

Fig. 2 is a front view of a portion of the head of the machine.

25 Fig. 3 is a cross sectional view through head substantially on the line 3—3 of Fig. 1 but with some of the parts in side elevation.

Fig. 3^a is a sectional view along the micrometer screw adjusting means for the presser cam, and showing the slide for retracting this cam.

30 Fig. 4 is a cross sectional view on the line 4—4 of Fig. 1.

Fig. 5 is a view of a detail.

Figs. 6 and 7 are perspective views of a cam.

35 Fig. 8 is a diagrammatic plan view of means for controlling the yarn feed finger and the presser cam.

In these drawings, 1 indicates the needle carrier or cylinder, 2 the needles, 3 sinkers, 40 4 pressers for the spring beard needles, 4^a the cam for operating the pressers and 5, 5^a the yarn guide fingers. We have shown two 45 yarn guide fingers but the machine may be equipped with any desired disposition and colors of yarn to make the striped pattern.

We have shown one of the yarn fingers at 5 in position to feed the yarn to the needles, and the other yarn finger 5^a in elevated position to lift the yarn out of work and if 50 we are feeding white yarn at say the finger 5 and blue yarn at the finger 5^a the striped effect in the circular fabric will be obtained

by allowing the finger 5 to feed its white yarn for a certain number of courses and then introduce the blue yarn by lowering 55 the finger 5^a and withdraw the white yarn by elevating its feed finger 5.

Each feed finger is carried by a shaft 6 journaled in a standard or post 7 attached to the cap or cam ring section 8 of the head. 60 The shaft has a collar 9 secured thereto provided with a projection 10 borne upon by a slide bar 10' extending laterally in respect to the post and guided in a groove or slot 11 formed in the base of the bracket or 65 standard 7. This slide bar is operated by a cam 12 forming the upper part of a rotary member which is connected to the vertical shaft 14 which has fixed thereto at its lower end a star wheel 15 arranged to be 70 struck and operated step by step rotatively by projections 16' 16'' of a member 16 carried by the rotary part of the machine, it being understood that the needle cylinder and sinker ring rotate and the cam rings 75 are stationary.

This member 16 is secured to the under side of the rotating sinker ring or bed 17.

When the high part 12' of the cam 12 acts upon the slide bar 10' and pushes it 80 towards the left in Figs. 1 and 2 the shaft 6 will be turned and the yarn feed finger will be lifted out of work, (see the finger 5^a) to withdraw the yarn from the needles so that knitting will cease at this feed and 85 conversely when the low part 12'' of the cam is opposite the end of the slide the feed finger will be forced down into work to feed yarn to the needles, this action being due to a spring 18 in a boss 19 of the bracket 90 or post 7 which spring acts upon a pin 20 bearing up under the end 21 of the yarn feed finger.

The yarn finger having been lowered will continue feeding its yarn until the star 95 wheel is set by the pattern mechanism into position to be again operated by the projections 16' and 16'' travelling with the rotary member of the machine.

The star wheel has four arms, two of 100 which 15' lie in a higher plane than the other pair of arms 15''. The pair of high arms 15' lie on one side of the star wheel adjoining each other, and the other pair, i. e.

the low arms 15" lie on the opposite side of the star wheel, adjoining each other.

The star wheel is movable vertically to different levels to bring either pair of its arms 15' or 15" into the horizontal path of movement of the travelling projections 16' 16". When the star wheel is in its low position the higher pair of arms 15' are in the plane of movement of the projections 16' 16" and therefore these projections in travelling past the star wheel will give it two step movements forward which it has done in Fig. 1 in the arrow direction, at the feed A in Fig. 1, each step being one quarter of a revolution so that the star wheel will advance one half of a revolution for each action of the actuator 16 thereon. This actuator has its two projections, one immediately behind the other and in the same horizontal plane, so that in passing the star wheel the first projection 16' will operate the star wheel one quarter of a revolution and the second projection 16" will immediately operate the star wheel another quarter of a revolution. Thereafter so long as the star wheel remains in the same horizontal plane at which it was last operated the travelling projections will pass the star wheel without giving it any further movement, and the yarn feeding finger will remain in the one position. In Fig. 1 the above actions are supposed to have taken place in respect to the star wheel at the feed A. When, however, the star wheel is adjusted, by suitable pattern mechanism not shown, to its other level this will bring the other pair of arms thereof into the horizontal plane of movement of the actuator so that the two projections 16' 16" will act respectively on the arms of this other pair and the star wheel will be turned step by step to perform another half revolution, thus turning the cam 12 to cause the shifting of the yarn feed finger from one position to the other.

In the organization illustrated the two high arms of the star wheel when operated cause the lowering of the yarn feed finger into operation as shown at feed A and the operation of the two low arms 15" 15' of the star wheel when operated cause the lifting of the yarn feed finger to its inoperative position as shown at feed B. In other words when the star wheel is in its lowermost position its high arms are in the path of movement of the projections 16' 16" and when these projections operate upon the two high arms the feed finger is thrown down into feeding position. In this action the first projection 16', or in other words the one leading in the direction of movement of the rotary member of the machine, see arrow α , operates upon one of the high arms and moves the star wheel one quarter turn and immediately thereafter the second pro-

jection operates upon the second high arm 15' of the star wheel and completes the half revolution of the cam 12 necessary to lower the yarn feed finger to its feeding position through the connections described. Having performed this shifting of the yarn feed finger any predetermined number of courses can be knit with the yarn fed through this finger, the other finger or fingers remaining out as long as the pattern mechanism calls for. This is due to the fact that having operated the two high arms of the star wheel in succession there is no other arm at the star wheel now in the plane of movement of the actuating projections 16' 16" and it requires the shifting (elevation in this case) of the star wheel vertically to its other position to bring the first one of the lower arms 15" into the path of movement of the actuating projections before the star wheel will be given its next step movement, and when this occurs it will be given immediately a second step rotary movement to complete the throwing out of the yarn feed finger because the second low arm will then be acted on by the second projection 16".

For shifting the star wheel vertically to its different levels a depressor member 23 is employed to force the star wheel downwardly and a spring 22 is employed to force the star wheel to its upper level when permitted to do so by the withdrawal of the depressor from over the shaft of the star wheel.

This depressor consists of an arm 23 having an inclined or cam-like blade or broadened outer end 23' said arm being mounted to turn about the axis 24 and having a second arm 25 formed therewith or attached thereto and connected by a rod 26 with pattern mechanism (not shown) of any suitable kind.

In the position of the parts shown at the left of Fig. 1, i. e. at the feed A at which the yarn feed finger is down in feeding position, the inclined depressor member has been moved to a position over the upper end of the star wheel shaft so that the shaft and star wheel have been depressed by the incline working thereon and the high arms of the star wheel have been operated by the projections 16' 16" which have acted thereon and turned the cam 12 to permit the spring 18 to throw the yarn finger down.

When the depressor member is operated by the pattern mechanism in the opposite direction its inclined under side moving outwardly over the upper end of the star wheel shaft, as at the yarn feed B, will so locate its lower inclined surface in respect to the shaft that the shaft may rise under the action of the spring 22 and thus the star wheel will be raised axially and its lowermost arms will be raised into the plane of movement of the projections 16' 16" to be

operated thereby, with the result that the cam 12 will be turned to lift the yarn feed finger out of work.

When this happens the yarn end will be 5 caught under a yarn end retaining finger 25' Fig. 5 pivotally mounted at 26' to a bracket 27 fixed to the cap member of the knitting head or ring, it being understood that any suitable form of cutter may be 10 employed at the center of the ring or head to sever the yarn which is lifted out of work.

This yarn end retainer has a shoulder 28 against which the yarn end lodges so 15 that it will be retained in a position ready to be introduced into the fabric again at a definite point when the yarn finger lowers.

This retainer finger works between the arms of the support 29 upon which the yarn rests, while borne upon lightly by the retainer finger.

Reverting to the mounting of the star wheel and its shaft, it will be seen from Fig. 4 that the said shaft at its upper end has a collar 30 surrounding it which is 25 slotted at 31 and receives pins 30' or a suitable projection on the star wheel shaft by which the shaft is permitted to move vertically but in both its high and low positions it will rotate the collar. This collar 30 is attached to the cam 12 by a pin 32 and a screw 33 arranged at diametrically opposite points, the collar having a flange 34 receiving the pin and screw. This connection will insure the proper relation being 35 maintained between the arms of the star wheel and the high and low parts of the cam 12. This is due to the fact that the collar can be attached to the cam in only one position by reason of the pin and screw 40 connection and the shaft of the star wheel can be attached to the collar in only one position due to the splined connections between them i. e. the pin and slot. In assembling these parts therefore the proper 45 timing of the action of the cam to that of the star wheel will be insured. Where, as in the present description and drawing, which we have chosen as an example illustrative of our invention, spring-beard needles are employed, means are provided 50 to prevent the needles from being pressed and casting off their old loops when the yarn is lifted therefrom and is out of work, as such action if not prevented would leave 55 the needles bare. For this purpose the presser cam 4^a which causes the pressing of the needle beards (for casting off the loops) through individually pivoted pressers 4 is retracted out of work when the yarn 60 feed finger corresponding to the said presser cam is lifted to stop feeding its yarn to the needles. For this purpose the presser cam has its shank 37 provided with a boss or stud 38 engaging a plate 39 slidably mounted 65 on top of the sectional cap ring and

guided in a recess in the base of the post or standard 7. This plate has a cam formation provided by notching its edge at 39' of V shape and the inclined side of this notch is engaged by a bar or pusher 40 arranged below the slide bar 10' and acted on by the lower cam section of the cam disc 12. This cam section has a high part 12^b and a low part 12^c and these are so disposed that just before the yarn finger is 70 lifted out of work by the cam portion 12, the high part 12^b of the cam will operate the notched slide 39 to retract the presser cam against the tension of its spring 41 so that the beards of the needles will not 80 be pressed and the old loops will not be cast off but will be held on the needles until such time that the feeding of new yarn thereto is resumed at the next active 85 yarn feed.

When the inoperative yarn feed finger is again lowered, by reason of the star wheel being shifted by the pattern mechanism and connections described, with its high arms 15' into the path of travel of the studs 16' 16'' 90 the low parts 12^c of the cam will come opposite the pusher bar 40 and the spring 41 will then move the presser cam to its operative position for pressing the needle beards. The yarn guide finger is thrown into feeding 95 position before the presser cam is restored to normal position, the interval between these actions being sufficient to allow the yarn where it is introduced to the needle row again to pass the pressing point so that 100 all of the needles opposite the presser will have been supplied with new yarn before the pressing takes place. This interval of time is due to the distance between the low points 12'' and 12^c measured counter clockwise in Fig. 1, 12'' being the point on the cam where the yarn finger is thrown in and 12^c being the point where the presser cam is thrown in.

In throwing the yarn finger out of operation the presser cam is first retracted, see the cams high part at 12^b and thereafter the yarn finger is lifted out of operation. For this purpose the point 12^b is spaced ahead 110 of the high part 12', the former 12^b acting in connection with the lower slide 40 to retract the presser cam and the latter acting on the upper slide 10' to turn shaft 6 to elevate the yarn feed finger.

The presser cam 4^a may be adjusted as 115 shown in Figs. 3 and 3^a, wherein is shown a rod 42 having its end screw threaded into the block 38 connected with the shank 37 of the presser cam. This rod 42 extends with a sliding fit through the screw threaded shank 42^a of a micrometer adjusting device, the finger wheel of which is indicated at 44. The rod 42 has a head 43 bearing against the outer face of the finger wheel. The screw threaded shank 42^a screws into a seat 125 130

in the cam ring. A spring 41 bearing against the end of this shank 42^a and against the shank 37 and stud 38 forces the presser cam 4^a inwardly towards the needles, the inward position of the said cam being determined by the head 43 bearing on the finger wheel 44. By turning the micrometer device 44, 42^a the presser cam can be set inwardly or outwardly in relation to the pressers 4, and the needle beards.

For convenience of manufacture the cam 12 is made in two parts pinned together. The upper part has the formation 12° 12'' and the lower part the formation 12°, 12°.

15 The post of the star wheel is much smaller in diameter than the opening through the cam and the opening through the cap section or cam ring 8 of the dial so that in replacing the dial cap it can be worked into place by catching up the butts of the sinkers which may have been misplaced and after it has been placed in position the collar 30 is introduced so that it will afford a bearing for the upper end of the star wheel shaft.

25 As before stated this collar enables the star wheel to be placed back in exactly the same position from which it was removed.

There is a guard 36 for the pressers. These pressers are liable to move out at their 30 lower ends when they are acted on by the cam, so that the presser or pressers next to the one being pressed will not be subjected to the influence of its spring and hence will be liable to jump out or get misplaced. The 35 guard will prevent this. The reason that the pressers move out at their lower ends is that they will pivot upon their noses instead of upon the point intended, and to avoid this action the guard is provided fixed to 40 the stationary cam ring at a point in the circle of the machine at which the pressing is done.

We claim:

1. In a circular knitting machine having a ring shaped head, a needle cylinder rotating within said ring, a yarn feed finger pivotally mounted on the ring, a star wheel turnable about a vertical axis, a vertical rotatable shaft therefor extending up through 45 the ring, a cam on the upper end of said shaft above the ring, a connection operated by said cam for operating the yarn finger, and means travelling with the needle cylinder for operating the star wheel, substantially as described.

2. In a circular knitting machine, the combination of a head member, a needle carrier, a yarn finger shiftable to and from position for feeding yarn to the needles, a star wheel turnable about a vertical axis, a vertical rotatable shaft therefor supported in the head of the machine, a cam on the said shaft above the star wheel, a connection for operating the yarn feed finger from 50 the cam, means for shifting the vertical

shaft with the star wheel to different levels, said star wheel having arms at different levels and means connected with the needle carrier for operating the star wheel as the one travels past the other, substantially as 70 described.

3. In combination in a circular knitting machine, a knitting head, comprising a support or carrier for knitting instruments, and a cam support having cams for operating said knitting instruments, a yarn feed finger shiftable into and out of yarn feeding position, a cam with connections between the same and the yarn finger for operating the latter, a vertical shaft carrying 75 said cam, said cam rotating in a horizontal plane above the cam support and means for giving said vertical shaft a step by step rotary movement to control the position of the yarn feed finger, substantially 80 as described.

4. In combination in a circular knitting machine, a knitting head, comprising a support or carrier for knitting instruments, and a cam ring having cams for operating 90 said knitting instruments, a yarn feed finger shiftable into and out of yarn feeding position, a cam with connections between the same and the yarn finger for operating the latter, a vertical shaft carrying 95 said cam, said cam rotating in a horizontal plane above the cam ring and means for giving said vertical shaft a step by step rotary movement to control the position of the yarn feed finger, said connections from the 100 cam including a push rod operated thereby, a rock shaft operated by the push rod for moving the yarn feed finger out of feeding position and a spring for operating the said finger into feeding position substantially 105 as described.

5. In combination in a circular knitting machine, a bed or carrier for knitting instruments, a cam ring having cams for operating said knitting instruments, a yarn feed 110 finger shiftable into and out of feeding position, a cam rotating in a horizontal plane and above the cam ring for operating the yarn feed finger, a vertical shaft carrying said cam and extending through and below 115 the cam ring, a star wheel on the lower end of said shaft having a pair of high arms and a pair of low arms, and a pair of projections connected with the knitting instrument carrier and means for shifting the star wheel vertically to bring either 120 its high arms or its low arms into the path of travel of the said projections, substantially as described.

6. In combination in a circular knitting machine, spring beard needles, a bed or carrier therefor, a cam ring and striping means comprising a plurality of yarn feed fingers disposed at separated points about 125 the needle circle, a presser cam at each 130

feed, and automatically operating connections for throwing a yarn finger into and out of operative position, means cooperating with said connections for automatically throwing the corresponding presser cam into or out of operative position, substantially simultaneously with the automatic throwing in or out of the yarn feed finger and while the machine continues in operation, substantially as described.

7. In combination in a circular knitting machine, spring beard needles, a bed or carrier therefor, a cam ring, presser means for the needle beards, a yarn feed finger, automatic means for throwing the same into and out of operation and means for automatically throwing the presser means out of operation when the yarn feed finger is moved to its inoperative position, said automatic means for operating the yarn feed finger and the presser means consisting of a rotary cam with connections to the yarn feed finger and presser means respectively, means for giving said cam a step by step movement, and pattern connections for controlling the operation of said means, substantially as described.

8. In combination in a circular knitting machine, spring beard needles, a bed or carrier therefor, a cam ring, presser means for the needle beards, a yarn feed finger, automatic means for throwing the same into and out of operation and means for automatically throwing the presser means out of operation when the yarn feed finger is moved to its inoperative position, said automatic means for operating the yarn feed finger and the presser means consisting of a rotary cam with connections to the yarn feed finger and presser means respectively, means for giving said cam a step by step movement, and pattern connections for controlling the operation of said means, said step by step moving means consisting of a star wheel on the shaft of the rotary cam and means on the needle carrier for operating said star wheel.

9. In combination, spring beard needles, a yarn finger, a presser, a cam for effecting pressing of the needle beards, a cam member having a portion to operate yarn finger connections and another portion to operate connections leading to the presser cam and means controlled by pattern connections for operating the said cam member, substantially as described.

10. In combination, spring beard needles, a bed therefor, a yarn feed finger, a cam for effecting pressing of the needle beards, a rock shaft carrying the yarn finger, a member arranged to retract the presser cam, a rotary cam, a pair of push rods operated thereby, one acting on the rock shaft of the yarn feed finger and the other operating upon the said member to retract the presser

cam and means for operating the said rotary cam including a star wheel and a member on the needle carrier for operating the same, substantially as described.

11. In combination, spring beard needles, a bed therefor, a yarn feed finger, a cam for effecting pressing of the needle beards, a ring shaped support, a cam rotatively mounted on the upper side of said supporting ring, a radially slidable plate connected with the presser cam, said plate having an inclined cam edge, a push bar operated by the rotary cam for operating the said plate and means for operating the rotary cam comprising a star wheel on the shaft thereof and means on the needle carrier for operating the star wheel, substantially as described.

12. In combination, spring beard needles, a presser cam, a rod connected with the presser cam, a spring for forcing the presser cam radially inward towards the center of the machine and a micrometer adjusting collar through which the rod is slidably, said rod having a head acting as a stop by resting upon the face of the micrometer adjusting device, and means for automatically retracting the presser cam comprising an upwardly projecting stud, a plate slidably mounted and engaging said stud, and means for operating the plate, substantially as described.

13. In combination in a circular knitting machine, a bed for knitting instruments, a yarn finger, means for shifting said yarn finger comprising a rotary step by step cam, a shaft carrying said cam, a star wheel on the shaft, means for operating the star wheel and a connection between the rotary cam and the shaft consisting of a collar having a splined joint with the shaft and having a connection with the cam which insures a certain relation between the said star wheel and the cam, substantially as described.

14. In combination in a knitting machine, a yarn feed finger, means for throwing the same into and out of operation including a star wheel and its shaft, the latter being vertically movable to shift the star wheel from one level to the other, said star wheel having two pairs of arms, one pair being in a higher plane than the other, contact means on a rotary part of the machine into line with which the pairs of arms are located by shifting the star wheel first to one level and then the other, a member adapted to operate upon the upper end of the shaft for depressing the same and connections leading to pattern means for operating said member substantially as described.

15. In combination in a knitting machine, a yarn feed finger, means for throwing the same into and out of operation including a star wheel and its shaft, the latter being vertically movable to shift the star wheel from one level to the other, said star wheel

- having two pairs of arms, one pair being in a higher plane than the other, contact means on a rotary part of the machine into line with which the pairs of arms are located by 5 shifting the star wheel first to one level and then the other, a member adapted to move over the upper end of the shaft for depressing the same and connections leading to pattern means for operating said member, 10 said depressor being pivotally mounted to swing in a horizontal plane, substantially as described.
16. In combination in a knitting machine, a yarn feed finger, a rockshaft carrying the 15 same, a post in which said rockshaft is journaled, a star wheel having arms at different levels, means for operating the star wheel, connections between the star wheel and the yarn feed finger for operating the latter and means for setting the star at different elevations including an arm pivoted 20 to the post and swinging in a horizontal plane and a cam member on the arm, substantially as described.
17. In combination in a knitting machine, a plurality of feeds, a yarn feed finger at each feed, a cam at each feed turning on a vertical axis, a star wheel turnable about a vertical axis, a vertical rotatable shaft 25 connecting each cam with its star wheel, means for operating the star wheels and a connection between each cam and the yarn feed finger corresponding thereto.
18. In combination with the rotary sinker 30 ring, a cam ring therefor, a yarn feed finger, a cam with connections therefrom to the yarn feed finger for operating the same, a shaft extending vertically through the cam ring and carrying said cam, a star wheel on the lower end of the shaft, means for operating the star wheel, said cam ring having an opening of larger diameter than the said shaft whereby said cam ring can be manipulated to engage the butts of the sinkers and 35 a removable bearing for the said shaft which will hold the shaft centrally in said large opening of the cam ring, substantially as described.
19. In combination with the rotary sinker 40 ring, a cam ring therefor, a yarn feed finger, a cam with connections therefrom to the yarn feed finger for operating the same, a shaft extending vertically through the cam ring and carrying said cam, a star wheel on the lower end of the shaft, means for operating the star wheel, said cam ring having an opening of larger diameter than the said shaft whereby said cam ring can be manipulated to engage the butts of the sinkers and 45 a removable bearing for the said shaft which will hold the shaft centrally in said large opening of the cam ring, substantially as described.
20. In combination in a circular knitting machine, a yarn feed finger, means for placing it in or lifting it out of yarn feeding position and a retainer for the end of the yarn comprising a loop shaped support and a member pivotally mounted and working between the sides of the said support, said member having a shoulder on its lower side 50 against which the yarn lodges, substantially as described.
21. In combination in a circular knitting machine, a needle bed, a sinker or web holder ring encircling the needle bed, a plurality of yarn feed fingers movably mounted at different points about the machine, a sectional removable cam cap for the sinker ring having cams on its under side to engage the butts of the sinkers, a star wheel at each feed, a shaft for each star wheel, said shafts passing up through openings in the removable sections of the cam cap larger than the diameter of the shafts, means operated by the shafts for throwing the yarn feed fingers into and out of work, and means for operating the star wheels, substantially as described.
22. In combination in a circular knitting machine, a needle bed, needles, radially movable elements cooperating with the needles, a supporting ring and a cam ring therefor, a plurality of yarn feed fingers disposed at different points about the machine, a shaft at each feed slidable vertically in relation to and rotatably supported by the cam ring, means on the upper end of each shaft for throwing the yarn feed fingers into and out of operative position, means on the lower end of the shaft by which it is rotated, means on the needle bed cooperating with the means on the lower end of the shaft for rotating it and means for moving the shaft vertically, substantially as described.
23. In combination in a circular knitting machine, a needle bed, needles, radially movable elements cooperating with the needles, a supporting ring and a cam ring therefor, a plurality of yarn feed fingers disposed at different points about the machine, a shaft at each feed slidable vertically in relation to and rotatably supported by the cam ring, means on the upper end of each shaft for throwing the yarn feed fingers into and out of operative position, means on the lower end of the shaft by which it is rotated, means on the needle bed cooperating with the means on the lower end of the shaft for rotating it and means for moving the shaft vertically, the means at the upper end of the shaft being splined thereto to be turned thereby but not to partake of the vertical movement of the shaft, substantially as described.
24. In combination in a circular knitting

machine, a plurality of feeds with a single yarn feed finger at each feed, spring beard needles, a bed therefor, a cam ring, a series of pressers, one for each needle, a cam at each feed for operating the pressers, automatic means for rendering the yarn feed fingers operative or inoperative in a prescribed order, and means for automatically retracting each presser cam so as not to operate the needle pressers, when the yarn feeding device corresponding thereto is rendered inoperative and while another feed finger continues to supply the needles and its corresponding cam continues to operate the pressers, substantially as described.

25. In combination in a multiple feed circular knitting machine, spring needles, a rotary needle carrier, radially movable instruments cooperating with the needles, a carrier therefor, a cam ring for said instruments, yarn guides mounted on said cam ring one at each feed and disposed at different points about the same, individual beard pressers, a presser cam at each feed for operating the pressers, and means at each feed mounted on the cam ring of said cooperating instruments for rendering the yarn feed fingers and the presser cam operative or inoperative automatically in a prescribed order while the machine continues in operation.

26. In a circular knitting machine having rotary movement always in one direction, the combination of spring beard needles, a plurality of yarn feed fingers disposed at separated points about the needle circle, a plurality of cams for effecting the pressing of the needle beards, one of said cams being disposed at each feed, means for throwing the yarn feed fingers severally into and out of operation in a prescribed order to form stripes and severally throwing the presser cams into and out of operation, while the machine continues its rotation in the one direction, and a device traveling with the rotary part of the machine for contacting with and operating said means, substantially as described.

27. In a circular knitting machine, the combination of needles, rotary needle carrier means, a plurality of feeds disposed at separated fixed points about the knitting head, with yarn guide means at each feed together with cams for making the needles knit, a star wheel at each feed rotatable about a vertical axis, at a point fixed in relation to the revolving needle carrier, a cam for each star wheel, means operated by the cams for rendering the feeds effective or ineffective in a prescribed order, said star wheels being shiftable to different levels and having arms at different levels,

means for shifting the star wheels, and means moving in unison with the revolving needle carrier for rotating the star wheels by striking the arms thereof, substantially as described.

28. In a circular knitting machine, a fixed ring shaped head, a needle cylinder rotating within the ring, a plurality of feeds disposed at separated fixed points about the knitting head, with yarn guide means, a presser cam and knitting devices at each feed, a star wheel at each feed rotatable about a vertical axis, at a point fixed in relation to the revolving needle cylinder, a cam for each star wheel, means operated by the cams for rendering the feeds effective or ineffective in a prescribed order, comprising connections for throwing the yarn guide means and presser cams in and out of working position, said star wheels being shiftable to different levels and having arms at different levels, means for shifting the star wheels, and means moving in unison with the revolving needle cylinders for rotating the star wheels by striking the arms thereof, substantially as described.

29. In combination, spring beard needles, a carrier therefor, a yarn feed finger, a cam for effecting pressing of the needle beards, a ring shaped support, a cam rotatively mounted, a radially slideable plate connected with the presser cam, said plate having an inclined cam edge, a push bar operated by the rotary cam for operating the said plate and means for operating the rotary cam comprising a star wheel on the shaft thereof and means on the needle carrier for operating the star wheel, substantially as described.

30. In a circular knitting machine, a fixed ring shaped head, a needle cylinder rotating within the ring, a plurality of feeds disposed at separated fixed points about the knitting head, with yarn guide means and knitting devices at each feed, a star wheel at each feed rotatable about a vertical axis, at a point fixed in relation to the revolving needle cylinder, a cam for each star wheel, means operated by the cams for rendering the feeds effective or ineffective in a prescribed order, said star wheels being shiftable to different levels and having arms at different levels, means for shifting the star wheels, and means moving in unison with the revolving needle cylinders for rotating the star wheels by striking the arms thereof, said star wheel shifting means comprising levers mounted above the knitting head and connections leading thereto, substantially as described.

31. In combination, a multiple feed knitting machine, a plurality of yarn feed fingers, one for each feed, an inclined rock shaft for each yarn finger on which it is

mounted to have up and down movement in a plane inclining upward and outwardly from the feeding point when the rock shaft is turned, means for turning the rock shafts, 5 in a prescribed order, and means for preventing the work from running off from the needles when the yarn fingers are raised, substantially as described.

32. In combination in a circular knitting machine for striping, needles, a plurality of feeds distributed at separated points about the machine, each including a yarn guide movably mounted to present the yarn to or remove it from the needles, each feed 10 including also a cam for manipulating the needles to knit, said cam being adjustable to render the needles non-operative for knitting, rotary cam means at each feed with connections therefrom to the yarn 15 guide and to the needle manipulating cam of said feed, said rotary cam means and said connections being timed to move the yarn guide and needle manipulating cam in prescribed order, to prevent dropping the 20 work in rendering the feed active or inactive, means rotating with the machine about the vertical axis thereof for causing operation of the rotary cam means, and means for determining the times that the rotary cam 25 means will be operated.

33. In combination in a circular knitting machine for striping, needles, a plurality of feeds, distributed at separated points about the machine, each including a yarn 30 guide together with means adjustable to make the needles perform or not perform their knitting actions, and pattern controlled connections for adjusting said means at the various feeds in a prescribed order, the needles 35 in passing the adjusted means, simply holding their old loop without knitting, said pattern controlled connections comprising a cam for each feed, a star wheel, a vertical shaft carrying the same and splined to the 40 cam, said pattern connection pushing the shaft with the star wheel downwardly, means for lifting the shaft with the star wheel attached thereto and means travelling with the needle carrier for turning the 45 star wheel.

34. In combination in a circular knitting machine, needles, a rotary needle carrier, a cam ring supporting needle operating cams, a yarn feed finger pivotally mounted at a 50 fixed point, a star wheel turnable about a vertical axis, a vertical rotatable shaft carrying the star wheel mounted at a fixed point in the cam ring, a cam on the shaft, a connection operated by the cam for 55 setting the yarn feed finger in or out of feeding position, means for adjusting the star wheel vertically to different levels, and means travelling with the needle carrier for operating the star wheel.

35. In combination in a circular knitting

machine, needles, a carrier therefor, means cooperating with the needles to perform knitting, a plurality of feeds with a yarn feed finger at each feed, a cam at each feed, a vertically shiftable shaft at each feed connected with the cam, pattern controlled means for shifting the said shafts vertically in prescribed order, means moving with the needle carrier for giving a rotary movement to the shafts when the latter are shifted vertically to a certain position, and means operated by the cams for changing the position of the yarn feed fingers in or out of feeding position, substantially as described. 70

36. In combination in a circular knitting machine, needles, a carrier therefor, means cooperating with the needles to perform knitting, a plurality of feeds with a yarn feed finger at each feed, a cam at each feed, a vertically shiftable shaft at each feed connected with the cam, pattern controlled means for shifting the said shafts vertically in prescribed order, means moving with the needle carrier for giving a rotary movement 75 to the shafts when the latter are shifted vertically to a certain position, and means operated by the cams for changing the position of the yarn feed fingers in or out of feeding position, substantially as described. 80

37. In combination in a circular knitting machine, needles, a rotary needle carrier, a plurality of feeds disposed at various points about the machine, a star wheel for each feed, vertical shafts carrying the star wheels, a cam splined to each shaft with connections leading therefrom to the feeds, for controlling the same, pattern means for pushing the shafts, downwardly and means for moving the shafts upwardly, said star wheels having high and low arms and contact means travelling with the rotary needle carrier for operating the star wheels, substantially as described. 100

38. In combination in a circular knitting machine, needles, a rotary carrier therefor, cams for operating the needles, supporting means for the cams, a yarn feed finger shiftable into and out of feeding position, a cam 105 rotating in a horizontal plane, above the cam support, for operating the yarn fingers, a vertical shaft carrying the cam and extending through and below the needle cam support, a star wheel on the lower end of said shaft having high and low arms, contact means travelling with the needle carrier for operating the star wheel and means for shifting the star wheel vertically to different levels in respect to said travelling 110 contact means.

39. In combination in a circular knitting machine, needles, a rotary carrier therefor, a plurality of feeds disposed about the machine at separated points, a star wheel at 115

each feed, said star wheels having high and low arms, means travelling with the rotary needle carrier for contacting with said arms, a vertically movable shaft carrying the star wheel, and means bearing on the upper end of the shaft for moving it downwardly, and means operated by the shafts for controlling the feeds, substantially as described.

40. In combination in a circular knitting machine, needles, rotary carrier means therefor, a plurality of feeds spaced apart at various points about the machine, and means for rendering said feeds active or inactive in a prescribed order, including a star wheel and cam for each feed, rotating about a vertical axis, contact means moving with the needle carrier for operating the star wheels, said star wheels having movement up and down to different levels in respect 10 to the path of travel of said contact means and having high and low arms to be hit thereby, and pattern controlled mechanism with connections extending over the knitting head and having up and down movement at their ends for shifting the star wheels vertically, substantially as described.

41. In combination in a knitting machine, a plurality of yarn feed fingers disposed at separated points about the same, a star wheel for each feed, a vertically movable shaft for each star wheel which is fixed thereto, said star wheel shaft being mounted in a fixed part of the machine, each of said star wheels having two pairs of arms extending substantially radially and horizontally, one pair being in a higher plane than the other pair, contact means rotating in 15

unison with a needle carrier to turn the star wheel step by step by acting upon the radial arms, and means for shifting the star wheel 40 with its shaft vertically to make the contact means act upon the arms, said shifting means including means engaging the upper end of the star wheel shaft for depressing it, and pattern controlled connections for 45 operating said depressing means, substantially as described.

42. In combination in a circular knitting machine, a plurality of feeds with a yarn feed finger at each feed movable to and from 50 feeding position, each feed including a cam to make the needles knit or not knit, a star wheel for each feed, a cam for each star wheel, travelling contact means moving in unison with a needle carrier for operating 55 the star wheel, a vertical shaft mounted in a fixed part of the machine one for each star wheel and its cam to which said star wheel is fixed and to which the cam is splined, said cam having two cam tracks, a 60 connection from one cam track for operating the yarn feed finger and a connection from the other cam track for operating the needle controlling cam of that feed, and means for moving the star wheel vertically 65 with its shaft so that the contact means will operate upon the arms thereof in prescribed order to turn the star wheel and its cam, substantially as described.

In testimony whereof, we affix our signatures. 70

KENNETH HOWIE.
WILLIAM O. TAYLOR.
